CLAIM

The ornamental design for a flood light with a solar panel, as shown and described.

DESCRIPTION

FIG. 1 is a perspective view of the flood light with a solar panel;

FIG. 2 is a front view of the flood light with a solar panel;

FIG. 3 is a rear view of the flood light with a solar panel;

FIG. 4 is a left side view of the flood light with a solar panel;

FIG. 5 is a right side view of the flood light with a solar panel;

FIG. 6 is a top view of the flood light with a solar panel; and,

FIG. 7 is a bottom view of the flood light with a solar panel.

The broken lines shown in drawings are included for the purpose of illustrating portions of the flood light with a solar panel, and form no part of the claimed design.
